CLOTHES DRIER

Claus H. Schultze, Brooklyn, N. Y.

Application April 24, 1935, Serial No. 17,925

3 Claims. (Cl. 211—94)

This invention relates to improvements in clothes driers.

One of the main objects of the invention resides in a clothes drier which enables the clothes to be dried to be hung thereon from within a room and the entire drier slid outwardly through a window opening clear of the sashes so as not to interfere with the sliding of the sashes, nor interfere with the entrance of light into a room 10 through the window, nor impair the view of the outside through the window. Such construction of clothes drier is intended to eliminate the reaching through a window to hang clothes and to remove them from the pulley supported type 15 of clothes line.

Another feature of the invention is to provide a clothes drier which is mounted for free sliding movement upon brackets secured at opposite sides of a window opening adjacent the top thereof to 20 enable the hanging and removal of the clothes and the sliding of the drier in and out through the window opening without stooping or leaning on the part of a user.

Another feature of the invention is the provision of a clothes drier which includes a rack 25 slidably supported in a novel manner to enable the easy removal of the rack from its support when not in use, and the positioning of the rack for use when desired.

A further feature of the invention is to provide a clothes drier which when extended through a window opening exterior of a building is capable of safely supporting the weight of its 35 capacity of wet clothes to be dried without the aid of guy wires, rods, and other like unsightly and cumbersome extraneous devices.

A still further feature of the invention is the provision of a clothes drier of the above mentioned type which is adjustable for use upon various widths windows, is simple and inexpensive of construction, and strong and durable for the purposes intended.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is a horizontal sectional view through a window showing my invention in top plan, the clothes rack being shown in extended position in full lines and in retracted position in dotted lines.

Figure 2 is a vertical sectional view on the line 2—2 of Figure 1.

Figure 3 is an enlarged detail vertical sectional view on the line 3—3 of Figure 1.

Figure 4 is an enlarged vertical transverse sectional view on the line 4—4 of Figure 2, but showing the hinged closure of the roller housing in open position in dotted lines.

Figure 5 is a perspective view of one of the supporting brackets per se.

Figure 6 is a side elevational view of one of the hinge locking pins.

Referring to the drawing by reference characters, the numeral 10 designates the side wall or window frame of a building, 11 a window opening 15 and 12 and 13, the upper and lower sliding sashes of the window. Secured to the outside of the wall 10 adjacent the top of the window opening 11 are horizontally disposed supporting brackets 14—14 and in view of the fact that the brackets 14—14 are identical in construction, a description of one will suffice for the other.

The brackets 14—14 are constructed in rights and lefts, and each includes a vertical attaching bar 15 preferably constructed of angle iron. 25

Welded or otherwise secured to one of the sides of the angle bar 15 and extending outwardly and horizontally therefrom is a horizontal arm 16, the inner end of the arm extending slightly beyond the bar 15 to provide an extension portion 30

17 having openings 18 therein for the passage of fastening elements. Welded to the vertical bar 15 is the short leg of an L-shaped brace 19, the long leg or arm of the brace 19 extending outwardly and being welded or otherwise secured adjacent the outer end of the horizontal arm 16. 35

The brace 19 is on substantially the same plane as the arm 16, and the short leg of the L-shaped brace constitutes a shoulder 20 for a purpose to be presently explained. Welded or otherwise 40

secured adjacent the top and bottom of the vertical bar 15 are outwardly converging diagonal brace bars 21, the outer ends of which are welded or otherwise secured to the outer side of the horizontal arm 16. The brace bars 21 and vertical 45

bar 15 form a substantially triangular shaped frame for the support of the horizontal arm 16. The bar 15 is provided with spaced openings 22 for the passage of fastening elements presently 50

to be described for use in securing the bracket in position upon the wall 10.

Welded to the inner side of the horizontal arm 16 at spaced distances therealong, are U-shaped housings 23 and journaled in each housing is a grooved roller 24. The outer side of each hous- 55

ing 23 at the top thereof is provided with spaced hinge pin knuckles 25 while hinged to the other side wall of each housing 23 as at 26, is an inverted U-shaped guide member 27, the free side 5 of the guide member 27 being provided with a hinge pin knuckle 28 for alignment with the knuckle 25 when the guide member 27 is in closed position. The guide members 27 are locked in closed position by a single locking pin 29 which 10 passes through the aligned hinge pin knuckles best seen in Figures 1 and 2 of the drawing. In order to captively connect the locking pin 29 to the bracket, one end of the pin is provided with an eye 30 while the inner end of the horizontal 15 arm 16 carries a chain 31, the free end of which is provided with a snap hook 32 for engaging the eye 30 of the locking pin 29.

By reference to Figures 1 and 2 of the drawing, it will be seen that the brackets 14 are positioned 20 adjacent the top of the window opening 11 exteriorly of the wall 10, with the roller supports facing inwardly. The extension portion 17 of each bracket fits against the side of the window opening 11 and fastening screws 33 pass through 25 the openings 18 into the wall 10. The shoulder portion 20 of the L-shaped brace 19 fits against the outside of the wall 10 as does the vertical bar 15. Fastening screws 34 pass through the openings 22 into the wall 10. From the description 30 thus far, it will be seen that the brackets 14 are rigidly supported upon the exterior of the wall 10 and extends outwardly therefrom in parallel relation.

Slidably supported by the brackets 14—14 is a 35 clothes rack R which is of substantially rectangular configuration in plan. The rack R includes a pair of inwardly spacing U-shaped frame sections 35—35, which are preferably constructed of rigid metal tubing and each U-shaped frame section comprises a side rail 36 and parallel end rails 40 or legs 37. Fixed in the free end of the legs 37 of one frame section 35 are rods 38 which telescope the respective legs 37 of the other frame section 35. By joining the end rails 37 of the 45 two frame sections 35 in this manner, the same may be adjusted to various widths for use in connection with windows of different widths. Threaded into the end rails 37 of the frame section and extending inwardly therefrom, are screw eyes 39 to which the ends of flexible clothes lines 40 are secured. The eyes are so positioned that the clothes lines 40 are disposed in spaced parallel relation lengthwise of the rack R.

In positioning the rack R for sliding movement 55 upon the brackets 14—14, the locking pins 29 are withdrawn from locking engagement with the guide members 27 and roller housing 23, whereupon the hinged guide members 27 may be swung to an open position upon the hinges 26 as shown 60 in dotted lines in Figure 4 of the drawing. When the guide members 27 are in open position, the side rails 36 of the rack R may be placed upon the rollers 24, after which the hinged guide members 27 are swung to closed position and the locking pin 29 inserted into the aligned eyes or hinge knuckles 25 and 28, thus locking the rack R in position upon the brackets for sliding movement inwardly and outwardly through the window opening 11. When the rack R is moved inwardly 65 of the window opening, the major portion of the rack will extend into the room through the opening, whereupon clothes to be dried may be hung upon the lines 40, after which the rack may be slid outwardly in order to dispose the entire rack 70

beyond the path of sliding movement of the sashes 12 and 13. By mounting the rack adjacent the top of the window opening, it is possible for a user to hang the clothes and remove them from the line 40 without stooping or leaning, it being understood that the upper sash is in a fully lowered position during the sliding of the rack back and forth through the window opening. There is sufficient clearance between the top of the window casing and the path of the rack R to 10 enable the free passage of any upwardly extending clothes pin which may be used in fastening the clothes upon the line. In the event that the clothes hung upon the lines depend below the plane of the sashes during movement of the rack 15 back and forth, the operator may lift the hung clothes clear of the sashes during such sliding movement. When the rack is not in use, the same may be drawn inwardly through the window opening, after which the pins 29 may be 20 removed from their locking position and the guide members 27 swung to open position, whereupon the entire rack R may be lifted free of the supporting bracket and stored away until further use 25 of the same is desired.

While I have shown and described what I consider to be the most practical embodiment of my invention, I wish it to be understood that such changes and alterations as come within the scope of the appended claims may be resorted to when 30 desired.

Having thus described the invention, what I claim as new and desire to secure by Letters Patent of the United States is:—

1. A clothes drier comprising a pair of brackets 35 adapted to be fixedly secured to the exterior of a building wall respectively at opposite sides thereof, a clothes rack frame, rollers mounted on said brackets and slidably supporting the opposite side rails of said frame, and releasable 40 guide members carried by said brackets and overlying the side rails of said frame for preventing up and down tilting of said frame.

2. A clothes drier comprising a pair of brackets 45 adapted to be fixedly secured to the exterior of a building wall respectively at opposite sides thereof, a rigid rectangular shaped frame having clothes lines strung lengthwise thereof, sets of spaced rollers mounted on said brackets and slidably supporting the respective side rails of 50 said frame, sets of hinged guide members mounted on said brackets and overlying the side rails of said frame, and releasable means for locking and unlocking the guide members of each set relative to said brackets.

3. A clothes drier comprising a pair of brackets adapted to be fixedly secured to the exterior of a building wall respectively at opposite sides thereof, each bracket including a horizontally disposed arm, a set of spaced rollers mounted on 60 said arm, a set of guide members hinged to said arm for swinging movement to a closed position clear of the same, a rigid rectangular shaped rack having parallel side rails resting upon the respective sets of rollers of the pair of brackets, said 65 guide members overlying said side rails when closed, interfitting hinge knuckles on said guide members and their related brackets, and a removable locking pin passing through the hinge knuckles of each bracket and the guide members mounted thereon for releasably locking the hinged guide members in closed position over the 70 respective rollers and side rails of the rack.

CLAUS H. SCHULTZE.
